CLAIM

The ornamental design for a doormat, as shown and described.

DESCRIPTION

FIG. 1 is a perspective view of a doormat according to a first embodiment of my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof taken along line 1-1;

FIG. 9 is a perspective view of a doormat according to a second embodiment of my new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a cross-sectional view thereof taken along line 2-2.

The broken lines shown in the drawings illustrating the environment that form no part of the claimed design.

1 Claim, 10 Drawing Sheets
